United States Patent Office

Des. 195,580
Patented July 2, 1963

195,580

ANIMATED TOY FIGURE

Frank Stanton, 1 W. 72nd St., New York, N.Y.

Filed May 4, 1962, Ser. No. 69,983

Term of patent 14 years

(Cl. D34—15)

I claim:

The ornamental design for an animated toy figure, as shown.
